JEWELRY-DISPLAY CASE.

1,059,561.

Specification of Letters Patent. Patented Apr. 22, 1913.

Application filed January 17, 1913. Serial No. 742,722.

To all whom it may concern:

Be it known that I, WILLIAM C. PARKS, a citizen of the United States, and resident of Brooklyn, in the county of Kings and State of New York, have invented certain new and useful Improvements in Jewelry-Display Cases, of which the following is a specification.

This invention relates to display receptacles and more particularly to a case for suitably exhibiting samples of jewelry, such as collar buttons and similar articles, a stock of which may be kept in the separate compartments of the receptacle.

The invention has for its objects to provide a display case which will prevent the tarnishing of the goods and keep the dust and air out of the stock compartments.

A further object is to provide means whereby the various kinds of articles in the compartments are brought to the attention of the buyer by samples, every particular style of which is secured to a cover and disposed over the articles of which it is a sample.

Other objects and the novel features of the invention will be apparent from the following description, taken in connection with the drawings, in which:

Figure 1 is a plan view of the display case; Fig. 2 is a cross section of the same along the line 2—2 of Fig. 1; and Fig. 3 is a view showing the outer and inner covers in slightly raised position.

Referring to the drawing, 10 designates a box of rectangular or other desirable form, which may be of pasteboard or any suitable material and provided with cross partitions 11 and 12 forming a plurality of compartments 13 in the box adapted to contain a variety of kinds of small articles of jewelry such as collar buttons.

Hinged along one side of the box and at the top of the compartments as at 14 there is an inner cover 15 which lies flat over each one of the compartments when it is closed and covers the same so that the articles will be retained in their respective compartments. The inner cover 15 may be of any suitable material and is preferably made of transparent celluloid or glass, and there is a tab 16 at one edge whereby the inner cover may be drawn out. As shown the compart-

ments 13 are only approximately one-half the depth of the box.

An outer cover comprising a frame 17, hinged along one edge of the box and having glued thereto a transparent portion 18 of some suitable material as glass or celluloid, fits over the top of the box and covers the same. The inner cover 15 as shown is made of celluloid and is provided with a number of pairs of short parallel slits 19, one pair of which is disposed over each compartment. Each pair of slits constitutes means for removably securing a sample, such as a collar button or other article, to the cover 15, the base of the collar button being supported on the narrow part between the slits as shown in the drawings. It will be understood that other suitable securing means may be employed.

There is an inner or second wall 20 which is of slightly greater height than the wall of the box 10 and is set flush against the inside of the box. The depending part of the frame 17 rests flush against the upper edge of the wall 20 and overlies the joining edges of the cover and box, providing an air-tight box.

The samples secured on the inner cover indicate the particular kind of article contained in the compartment immediately below the same. The samples further prevent the inner cover from raising and allowing the articles in the several compartments to become mixed. Some of the samples in the space intervening between the covers may be of such a height as to touch the outer cover and prevent any movement whatever of the inner cover when the box is turned over while the outer cover is kept closed, yet it is not necessary that the samples touch the said outer cover but merely contact with the same before the inner cover opens sufficiently to permit the escape of the articles in some of the compartments into other compartments.

It will be seen that the construction provides a jewelry display case in which the outer and inner cover when closed are sustained in spaced relation by the samples. The inner cover is prevented from any appreciable movement when the case is closed. The samples may readily be taken off and put on, thus permitting a change of assort-

ments. The stock as well as the samples are not readily handled by the customer but at the same time are exhibited to advantage, and are kept bright by keeping them free 5 from dust and air.

It will be clear that changes may be made without departing from the spirit of the invention and it is therefore to be understood that the invention is not limited to the exact 10 details as shown and described.

Having thus described the invention, what is claimed is:—

1. In a jewelry display case of the class described, the combination of a receptacle 15 having compartments adapted to contain articles of jewelry, an inner cover constructed to close said compartments, an outer cover, and means for supporting samples of the articles contained in the several compartments 20 on one of said covers and over the respective compartments whereby the samples are arranged to sustain said covers in spaced relation when the covers are closed, thereby retaining the articles in their respective compartments.

2. A jewelry display case comprising the combination of a receptacle having in its lower part compartments adapted to contain 25

articles of jewelry, a transparent outer movable cover for the receptacle, an inner cover 30 adapted to close the compartments, and means for supporting samples of said articles on the inner cover whereby said articles are adapted by engagement with the outer cover to hold the inner cover closed so as to 35 retain the articles in their respective compartments when the outer cover of the receptacle is closed.

3. A jewelry display case comprising the combination of a receptacle having in its 40 lower part compartments adapted to contain articles of jewelry, a transparent outer movable cover for the receptacle, a transparent inner movable cover adapted to close said compartments, and means for supporting 45 samples of the articles on the inner cover for maintaining the inner cover closed when said outer cover is closed, and thereby retaining the articles in their respective compartments. 50

In testimony whereof I affix my signature in presence of two witnesses.

WILLIAM C. PARKS.
